Primary Examiner—Dominic Simone*Assistant Examiner*—Cheri Cohen*Attorney, Agent, or Firm*—Rhodes, Coats & Bennett[57] **CLAIM**

The ornamental design for a golfer's plumb, as shown and described.

DESCRIPTION

FIG. 1 is a perspective view of a golfer's plumb showing my new design; and,

FIG. 2 is an enlarged front elevation view thereof, with the remaining views being identical.

The cord is shown fragmented in FIG. 2 for ease of illustration.
